(57) **CLAIM**

The ornamental design for a anti-sliding device assembly, as shown and described.

DESCRIPTION

FIG. 1 is a bottom plan view of a base plate portion of the anti-sliding device assembly according to the present invention;

FIG. 2 is a top plan view of the base plate portion of FIG. 1;

FIG. 3 is a perspective view showing the bottom portion of a receptacle for fixing rods used with the portion of FIGS. 1 and 2;

FIG. 4 is a perspective view showing the top portion of the receptacle of FIG. 3;

FIG. 5 is a perspective view of one of the fixing rod portions of the anti-sliding device assembly; and,

FIG. 6 is a perspective view of the complete anti-sliding device assembly.
